UNITED STATES PATENT OFFICE.

FERDINAND RIES, OF NEW YORK, N. Y.

DIAMOND-GRINDER.

1,269,002.

Specification of Letters Patent. Patented June 11, 1918.

Application filed April 13, 1917. Serial No. 161,725.

To all whom it may concern:

Be it known that I, FERDINAND RIES, residing at New York, in the county of New York and State of New York, have invented 5 a new and Improved Diamond-Grinder, of which the following specification is a full disclosure.

This invention deals with mechanism for cutting and polishing precious stones, such 10 as diamonds, and it proposes a simple, compact, inexpensive and convenient apparatus for this purpose.

Heretofore devices for successfully polishing stones have been commercially available, 15 but said devices have either been of restricted capacity because of the necessity of releasing the gem in order to reposition it for the different facets and have therefore been inconvenient to use.

20 The primary object of this invention is to create and render available an apparatus which will not only be of the utmost convenience in point of usage, but will also be sufficiently simple to enable it to be manufactured and sold at a price within the reach 25 of all those having need for such devices.

Other objects will be in part obvious from the annexed drawings and in part indicated in connection therewith by the following 30 analysis of this invention.

This invention accordingly consists in the features of construction, combination of parts and in the unique relations of the members and in the relative proportioning 35 and disposition thereof; all as more completely outlined herein.

To enable others skilled in the art so fully 40 to comprehend the underlying features thereof that they may embody the same by the numerous modifications in structure and relation contemplated by this invention, drawings depicting a preferred form have been annexed as a part of this disclosure, and in such drawings, like characters of reference denote corresponding parts throughout all the views, of which:—

Figure 1 is a side elevation of an apparatus embodying this invention showing the different parts thereof in position for grinding a stone. Fig. 2 is a section through line II—II of Fig. 1 showing the details of the mounting of the so-called guillotine. Fig. 3 is a rear elevation of the apparatus, certain parts being broken away. Fig. 4 is a plan of the apparatus showing all the elements thereof duly assembled. Fig. 5 is a section

through line V—V of Fig. 4 showing in detail the adjusting means for the dop holder. Fig. 6 is a section through line VI—VI of Fig. 4 showing the details of the dop and 60 the fingers for determining the position of the same. Fig. 7 is a bottom view of the dop. Fig. 8 is a view of a finger for determining the position of the stone. Fig. 9 is a view of the end of the arm supporting the 65 dop holder showing the numbering thereon for assisting the grinder in cutting the stone. Fig. 10 is a view of the tongs for determining the position of the stone for the different settings thereof. Fig. 11 shows a modified 70 form of tongs. Fig. 12 is a detached view of a simplified modification of the dop and adjacent parts. Fig. 13 is an end elevation of the same. Fig. 14 is a bottom view thereof. Fig. 15 is a section through line XV— 75 XV; and Figs. 16, 17 and 18 are perspectives of different forms of fingers for affixing the position of the stone.

Referring to the drawings, this apparatus is designed to be positioned on the table A 80 which is adjacent a conventional lap or rotating wheel employed in polishing diamonds. This apparatus consists of a base B which is retained by a pin 1 in definite relation with the main table A and is also provided with two leveling screws 2 and 3 at its forward end. Surmounting this base is a frame C which is slidably connected to the base B by means of a dovetail slideway 4 which extends horizontally so as to permit 90 the frame to be moved toward and away from the lap for purposes of adjusting the position thereon of the stone. A thumbscrew 5 serves to secure the frame C in its adjusted position. This frame provides a 95 vertical slideway formed of the risers 6 and 7 and the retaining strips 8 and 9.

A carriage D slides freely up and down in the ways of these uprights and this carriage in turn supports the various elements 100 which position the gem on the lap. The carriage is formed of a body portion 10 provided with sliding surfaces and a boss 11 which receives the stem 12 of a socket member E. This boss 11 is split at 13 and is 105 provided with a clamping screw 14 to enable the stem 12 to be rigidly clamped against turning after it has been set in its predetermined position. It may be explained here that by lifting the carriage D the gem 110 is removed from the lap and may be inspected or adjusted and for the purpose

of controlling the cutting of the stone and the inspection thereof it is desirable to conveniently add to the weight of the carriage or to counter-balance the same. To that end, a bifurcated lever 15 is pivoted to the boss 16 extending laterally from the wing 17 and this lever embraces the boss 11 of the carriage D. Pivoted adjacent the lever 15 is an arm 18 which has a knuckle joint in connection with the lever 15 so that when it is in the position shown by Figs. 1 and 4 the weight 19 will bear down the lever 18 and this in turn will act through the lip 20 to engage the shoulder 21 of the lever 15 with the effect that said bifurcated lever will be uplifted and exert a corresponding pressure on the carriage D thereby compensating for the weight thereof. In order that this may be regulated, the weight 19 is adjustable along the arm 18 and may be fixed in any predetermined station thereon by means of a thumbscrew 21. Accordingly, when it is desired to uplift the carriage D it will be convenient to swing over the weight 19 and compensate thereby for the weight of the carriage which will render easy its rising. This is further facilitated by means of another lever 22 which is pivoted at 23 to a stud 24 projecting laterally from the wing 25. Said lever 22 extends alongside of the main portion 10 of the carriage D and takes under a roller 26 carried by a pin 27 secured to the face of the carriage D. The lever has a thumb-piece 28 whereby it may be depressed to raise the carriage and enable the carriage to be held uplifted for a while, a pawl 29 is pivoted at 30 to the carriage and by means of a spring 31 is normally held against a stop pin 32 so that when the carriage is lifted this pawl 29 may catch on the pin 33 projecting from the upper cross-piece 34 of the arm C and thereby hold the carriage in its elevated position. To limit the downward movement of the carriage, a stem 35 extends upwardly and passes through a hole 36 in the cross-piece 34 and terminates in a threaded end 37 which carries a thumbscrew 38 which may be graduated in correspondence with a scale on the frame C to indicate the downward movement of the carriage and to limit the same to any predetermined degree.

As the gem is being worn away by the 55 lap, the carriage will gradually descend and in order that the extent of this movement may be readily and closely followed, a sensitive indicator is associated with the carriage so as to magnify the movements 60 thereof when in its lower or gem-cutting position. To avoid interference during the uplifting of the carriage D this indicator is detachably connected with the carriage. This is accomplished by pivoting an 65 elongated needle or pointer 39 to a stud 40

secured to the upright 7 of the frame C. The short end of the indicator 39 extends slightly beyond this stud in position to be depressed by a pin 41 secured to the carriage D and projecting through a slot 42 in 70 the upright 7. When the carriage D is lifted the pin 41 will, of course, be entirely clear from the short arm of the lever-indicator 39, but when the carriage is down, contact will be established with the consequence that the extreme end 43 of the lever will move rapidly and the extent of the movement will be indicated by a scale 44 secured to the frame C as shown best by Fig. 2. By means of the construction thus 75 far described, the rate of wear of a gem is accurately under observation at all times and its extent is easily limited and the gem can readily be lifted for purposes of inspection, etc.

In order to enable angles for cutting the different facets to be accurately determined, this invention proposes various elements so concatenated that the angular relation of the one to the other can be readily varied 80 and adjusted to enable the stone to be sloped at any angle and in any direction such as would be needed for purposes of cutting the facets thereon. In this embodiment several elements E, F, G, H and I are thus 85 arranged together. Element E is in the nature of a socket member pivoted to the carriage D about a horizontal axis and adapted to be secured in its position by means of the clamp screw 14, and this element E is provided with a pointer 45 (see Fig. 1) which co-operates with the scale 46 on the carriage D. This enables the angular relation between the parts to be always under inspection and control. A thumbscrew 90 47 bearing against the lower part of the member E in offset relation with its pivot assists in leveling the parts and in securing an accurate setting of the element E with 95 relation to carriage D.

An elongated arm F preferably in the nature of a rod extends from the socket member E to the lap which is at some distance away and at its extremity carries certain other elements providing for angular adjustments. This arm F passes through a horizontal bore in the socket member E and may be clamped in any desired angular relation therewith by means of the clamp screw 48 compressing the wings 49 of the saw-cut 50. In order to facilitate the attainment of any desired angular relation this invention proposes adjusting means consisting of an L-shaped abutment 51 rising from the arm and terminating along side of a movable stop-pin 52 which rises upwardly from a part 53 screw-threaded to an adjusting screw 54. A scale 55 enables the position of the stop-pin 52 to be accurately ascertained and thus 100

to obtain an accurate angular adjustment of the bore or arm F by bringing the abutment 51 thereof into contact with the pin 52.

At its outer end the arm F is squared as indicated by 56 and it is provided with an aperture 57 for receiving the stem 58 of the member G. A clamping-nut 59 is screw-threaded through said stem and enables the part G to be positioned in any one of eight different relations with the arm F; said relations being indicated by numerals 60 to enable the user to cut stones in accordance with the conventional system. The lower end of the member G is bifurcated and receives a holder H which is pivoted thereto about a horizontal axis by means of the pin 61. A lock-nut 62 holds the parts together.

The holder H in the simplified modification as shown by Figs. 12 to 14 has an extension 63 projecting transversely to the pivot 61 so as to be located in offset relation therewith. It is provided also with a socket 64 which is tapered and is adapted to receive the conical end 65 of the collet I. A nut 66 screw-threaded to the threaded stem 67 of the collet serves to draw it home and lock it in position. It is desirable, in order that different facets of the stone may be cut, to affix the collet I in different positions in the holder H and to enable this to be done accurately, the collet is provided with a circular flange 68 knurled so that it may be readily turned by the fingers and having a circumferential series of holes 69 which may be registered with the index pin 70 that is mounted in the socket 71 in the extension 63 by means of a spring 72 has its slightly tapered end thrust into the selected hole. These holes are numbered alternately from 1 to 8 as shown by Fig. 7, for the guidance of the user in indexing the collet I.

The gem is embedded in a conical dop J which is seated in the conical socket 73 of the collet I.

A very important characteristic of this invention resides in the instrumentalities for enabling the gem undergoing polishing to be accurately repositioned for the different facets. It should here be explained that this gem is partially embedded in position, but it is highly desirable that as much as possible of the gem should be exposed so that a clear view may be had of it and so that the position will not interfere with the polishing. This occasions much trouble owing to the fact that necessarily the gem cannot be firmly held and when it is lifted out of contact with the lap, it is likely to fall out or become more or less displaced. If this happens, it is obvious that the angles must be entirely reset throughout the apparatus described in the foregoing thereby causing a great loss of time and tending to produce imperfect work. I have, however, succeeded in devising a system whereby the

gem will always be held visibly in place. To that end, the collet I (see Figs. 12 to 18) is provided with a series of prong-receiving sockets 74. When the gem K in the dop J is initially mounted in the collet, a number of prongs L are mounted in said sockets and secured therein by set screws 75 so as to bring the ends of the prongs bearing firmly against the sides and the back of the gem, as shown in Fig. 14. This affords a clear and unimpeded region of the gem which can now be placed against the lap by a suitable adjustment of the machine and the polishing of the facet can be completed. When said facet is finished, it becomes necessary to lift up the dop and to reposition it. This requires that one or more of these prongs L shall be removed to clear another region of the gem. According to this invention, another prong will now be inserted in another one of the sockets 74 and brought against the polished facet; one or more additional prongs being used as may be desired. It is now possible to remove one or more of the original prongs without however permitting the gem to shift its position. The dop can now be given its new position and the polishing may be again resumed. These operations are continued until it is completed.

As shown by Figs. 6 and 8, a supplemental prong M may be used to bear directly against the face of the gem, and in place of using the independent prongs shown by Figs. 16 to 17, a universal prong N such as shown by Figs. 10 or 11 may be used. A holder H in this modification is provided with a portion 76 having a socket 77 adapted to receive the stem 78 of the universal prong N and held therein by means of a set screw 79. This universal prong has a pair of fingers 80 and 81 pivotally secured to a part 82 connected with the stem 78. A clamping screw 83 suffices to draw the ends of the fingers 80 and 81 together, like an ordinary pair of dividers to clamp the sides of the gem. In the modification shown by Fig. 11 the fingers 84 form tongs loosely screw-threaded to the shaft 85 which in turn is mounted on a part 86 projecting from the stem 78. The ends of the fingers 84 carry pins 87 that have a certain amount of free play in the slots 88 in the wings 89, the whole constituting a self-adjusting device.

Without further analysis, the foregoing will so fully reveal the gist of this invention that others can by applying current knowledge readily adapt it for various applications without omitting certain features that, from the standpoint of the prior art, fairly constitute essential characteristics of the generic or specific aspects of this invention, and therefore such adaptations should and are intended to be comprehended within the meaning and range of equivalency of the following claims.

Having thus revealed this invention, I claim as new and desire to secure the following combinations of steps and elements, or equivalents thereof, by Letters Patent of the 5 United States:—

1. A machine of the nature disclosed combining a base; a frame horizontally adjustable thereon and consisting of an upright frame and a carriage vertically slidable thereon; a member horizontally pivoted to 10 said carriage; an arm pivoted transversely to said member; a support vertically pivoted to the extremity of said arm; a member horizontally pivoted to said support; and a 15 dop holder vertically pivoted to said member.
2. A machine of the nature disclosed combining an upright frame and a carriage vertically slidable therein; a gem holding instrumentality having movement in all directions mounted on said carriage; means for counterbalancing the weight of said carriage; and means for rendering said counterbalancing means effective or ineffective. 20
3. A machine of the nature disclosed combining an upright frame and a carriage vertically slidable therein; a gem holding instrumentality having movement in all directions mounted on said carriage; a lever 25 bearing against said carriage; and a weight pivoted to said lever to exert either an upward or a downward action thereon.
4. A machine of the nature disclosed combining an upright frame and a carriage vertically slidable therein; a gem holding instrumentality having movement in all directions mounted on said carriage; a pivoted indicating needle having an elongated extension coöperating with a fixed scale; and 30 means movable with said carriage for acting on said needle closely adjacent its pivot to magnify movements of said carriage.
5. A gem polishing machine including a frame having a vertically movable carriage; 35 a member pivoted to said carriage about a horizontal axis; an elongated arm pivoted to said member transversely to said axis; adjusting means for determining the angular relation between said arm and member; and 40 a dop adjustably carried by said arm.
6. A gem polishing machine including a frame having a vertically movable carriage; a socketed member horizontally pivoted to 45 said carriage; an elongated rod adjustably seated in the socket of said member; a clamping means for determining the angular 50

relation between said two last mentioned parts; and a dop adjustably carried by said arm.

7. A gem polishing machine combining a 60 downwardly movable mechanism having an arm located over a lap; a holder having an offset extension pivoted to said part; a collet depending from said holder and rotatable thereon; and an indexing device for determining the position of said collet.

8. A gem polishing machine combining a downwardly movable mechanism having an arm located over a lap; a collet having a 65 dop-receiving socket and also a number of 70 symmetrically disposed sockets; a gem-carrying dop carried by said collet; and a series of prongs adapted to be individually secured in said sockets and to be independently shifted from one socket to another. 75

9. A gem-grinding mechanism combining a member provided in its end with a recess adapted to seat a gem; a part having a plurality of sockets disposed around the axis of said seat; a few gem-retaining prongs 80 adapted to be inserted into said sockets each to exert pressure on said gem in the direction of the axis of said member and grouped to expose a predetermined side of the gem to the action of a lap; and means for clamping 85 said prongs in said sockets, whereby the prongs may individually be shifted in succession to other sockets to expose the different sides of the gem to the action of the lap without releasing said gem or permitting it 90 to shift its mounting in said seat.

10. A gem-grinding mechanism combining a holder; a mounting for said holder; indexing means for adjustably fixing the angular relations of said parts; means for 95 seating a gem in definite relation to said holder; a plurality of independent diversely shaped fingers; and means enabling one or more of said fingers to be independently secured to said holder and to be individually 100 shifted in position; whereby the fixed relation of said gem to said holder will always be maintained by some of said fingers during the re-adjustment of other fingers.

In witness whereof, I hereunto subscribe 105 my name, as attested by the two subscribing witnesses.

FERDINAND RIES.
